UNITED STATES PATENT OFFICE

170,070

TELEVISION BROADCAST TRANSMITTER

Martin Silver and Ervin M. Bradbury, Fairlawn,
and Raymond B. Lewthwaite, River Edge, N. J.,
assignors to Federal Telecommunication Laboratories,
Inc., Nutley, N. J., a corporation of
Delaware

Application March 3, 1953, Serial No. 23,871

Term of patent 14 years

(Cl. D56—4)

To all whom it may concern:

Be it known that we, Martin Silver, Ervin M. Bradbury and Raymond B. Lewthwaite, have invented a new, original, and ornamental Design for Television Broadcast Transmitter, of which the following is a specification, reference being had to the accompanying drawing, forming a part hereof, wherein:

Fig. 1 is a perspective view of a television broadcast transmitter showing our new design, the unshown side being substantially like the side shown.

Fig. 2 is a rear elevational view thereof.

We claim:

The ornamental design for a television broadcast transmitter, as shown and described.

MARTIN SILVER.
ERVIN M. BRADBURY.
RAYMOND B. LEWTHWAITE.
